UNITED STATES PATENT OFFICE

2,447,596

VACCINATION DEVICE

Foster S. Price, Sterling City, Tex.

Application June 3, 1947, Serial No. 752,154

3 Claims. (Cl. 128—253)

1

This invention relates to inoculation devices, and more particularly to inoculation devices for animals employing the so-called "scratch" method.

A main object of the invention is to provide a novel and improved vaccination device which is very simple in construction, easy to use and reliable in operation.

A further object of the invention is to provide an improved vaccination device which is inexpensive to manufacture, sturdy in construction and economical in its use of vaccine materials employed for inoculation.

Further objects and advantages of the invention will become apparent from the following description and claims, and from the accompanying drawings, wherein:

Figure 1 is an elevational view of a vaccination device constructed in accordance with the present invention.

Figure 2 is an enlarged vertical cross-sectional detail view taken through the lower portion of the inoculation device of Figure 1.

Figure 3 is an enlarged perspective view of a brush tip member employed with the vaccination device of Figure 1.

Figure 4 is an enlarged horizontal cross-sectional view taken on line 4—4 of Figure 2.

Figure 5 is an enlarged vertical cross-sectional detail view illustrating an alternative form of the invention.

Referring to the drawings, 11 designates an elongated rod which is employed as the handle of the vaccination device. Secured in the end portion of handle rod 11 is a needle member 12 projecting substantially axially from the end of the rod. The end portion of rod 11 is somewhat tapered and secured thereon is a sleeve member 13 formed at its lower portion with an axial bore through which the needle 12 passes. Secured to the end of sleeve member 13 is a tip member 14 also axially bored for the passage of said needle. Tip member 14 carries a tuft of brush bristles 15 which terminate substantially flush with the sharp tip of needle 12.

Instead of employing a tip member 14 the sleeve member 13 may be hollowed out at its lower portion and the tuft of brush bristles secured directly in the hollowed-out portion, as shown in Figure 5.

In operation, the operator dips the brush end 15 of the device into the vaccine receptacle and merely scratches the skin of the animal or subject by drawing the brush end of the device across the skin. The vaccine is smeared across the

2

scratch by the brush bristles 15 during this process and thereby completes the inoculation. It is impossible to miss the scratch because the brush bristles carrying the vaccine automatically follow the scratching needle tip.

The brush bristles are made preferably short so as to absorb only a small amount of vaccine. The instrument is therefore economical in the use of vaccine as well as positive in its inoculating action.

While certain specific embodiments of a vaccination device have been disclosed in the foregoing description, it will be understood that various modifications within the spirit of the invention may occur to those skilled in the art. Therefore, it is intended that no limitations be placed on the invention other than as defined by the scope of the appended claims.

What is claimed is:

20. 1. A vaccinating device comprising a tubular body member having a stepped bore defining a relatively large diameter upper bore portion and a relatively small diameter lower bore portion opening through the lower end of said body member, said bore portions defining a stop shoulder therebetween, a brush secured to the lower end of said body member, and a handle member having a lower end portion removably insertible in the large diameter portion of said body member and a needle projecting axially from the lower end of said handle member to extend through said smaller diameter bore portion of said body member, said lower end portion being insertible into the bore of said body member so as to engage the lower end thereof with said stop shoulder whereby the degree of projection of said needle below the lower end of said body member is positively limited to a position within said brush.

2. A vaccinating device comprising a tubular body member having a stepped bore defining a relatively large diameter upper bore portion and a relatively small diameter lower bore portion opening through the lower end of said body member, said bore portions defining a stop shoulder therebetween, a brush secured to the lower end of said body member, and a handle member having a lower end portion removably insertible in the large diameter portion of said body member and a needle projecting axially from the lower end of said handle member to extend through said smaller diameter bore portion of said body member, said lower end portion being insertible into the bore of said body member so as to engage the lower end thereof with said stop shoulder whereby the degree of projection of said needle

below the lower end of said body member is positively limited to a position within said brush, said brush comprising a cap positioned on the lower end of said body member.

3. A vaccinating device comprising a tubular body member having a stepped bore defining a relatively large diameter upper bore portion and a relatively small diameter lower bore portion opening through the lower end of said body member, said bore portions defining a stop shoulder therebetween, a brush secured to the lower end of said body member, and a handle member having a lower end portion removably insertible in the large diameter portion of said body member and a needle projecting axially from the lower end of said handle member to extend through said smaller diameter bore portion of said body member, said lower end portion being

5 insertible into the bore of said body member so as to engage the lower end thereof with said stop shoulder whereby the degree of projection of said needle below the lower end of said body member is positively limited to a position within said brush, said brush comprising a bunch of bristles securably inserted in a socket provided in the lower end of said body member.
